 The Hoover Company, North Canton, Ohio, a
 corporation of Ohio

Application February 25, 1942, Serial No. 432,207

20 Claims. (Cl. 62—5)

This invention relates to refrigeration and more particularly to an arrangement whereby an absorption refrigerating apparatus can be assembled with a domestic refrigerator cabinet with the top of the evaporator at a higher level than the bottom of the condenser, thus reducing the total height of the apparatus and rendering a larger proportion of the cabinet space available for food storage purposes.

In designing refrigerating apparatus for application to the domestic refrigerating field, the apparatus must be designed very compactly so that it can be properly installed on standard sized domestic refrigerator cabinets. In the compression refrigerating field this is not particularly difficult since the only limitation as to the location of the parts is that the evaporator be positioned in the food storage compartment. In the absorption refrigerating field, however, the problem is more difficult because the parts usually must be located in definite locations relative to each other insofar as vertical height is concerned. Thus anything which will reduce the total vertical height of the apparatus will be advantageous.

According to this invention the vapor flowing from the generator to the condenser is utilized to raise refrigerant liquid from the condenser to a higher level from where it can flow by gravity into the top of the evaporator. By this arrangement it is possible to position the condenser at the same level or below the evaporator making it unnecessary to position the entire condenser above the evaporator and to this increase the total height of the apparatus. This renders it possible to make the total cabinet height smaller for a particular food storage capacity or to reduce the space occupied by the apparatus and increase the food storage capacity.

More specifically, according to this invention, the vapor from the generator flowing to the condenser is passed into liquid refrigerant from the condenser so as to form a vapor lift pump which raises the liquid refrigerant to a vapor separation chamber above the top of the condenser and the evaporator wherein the vapor is separated from the liquid and flows to the condenser while the liquid refrigerant flows by gravity to the evaporator through a liquid trap, which prevents vapor from reaching the evaporator.

As will appear hereinafter this invention has been described as being particularly applicable to an absorption refrigerating apparatus of the intermittent type. It is not so limited in its application but can be applied to other types of absorption refrigeration machines as well.

Other objects and advantages of this invention will become apparent as the description proceeds when taken in connection with the accompanying drawings in which:

5 Figure 1 is a diagrammatic representation of a dual intermittent absorption refrigerating machine with this invention applied thereto;

10 Figure 2 is a diagrammatic representation of a single intermittent absorption refrigerating machine with this invention applied thereto; and

Figure 3 shows the parts of the machine of Figure 1 properly arranged and assembled with a standard domestic refrigerator cabinet.

Referring to Figure 1 of the drawings, A, A' represent two generator-absorbers, C, C' two primary condensers and E, E' two evaporators. The absorbent receiving space of the generator-absorbers A, A' are connected to the condensers C, C' by conduits 10, 10' and conduits 11, 11', the latter forming vapor lift pumps whose operation will be described more particularly hereinafter. The conduits 11, 11' open at their upper ends into vapor separation chambers 12, 12', the vapor space of which is in open communication with the top of the condensers C, C'. The condensers C, C' have a downwardly inclined slope throughout and are connected by liquid traps 13, 13' to the junction of conduits 10, 10' and 11, 11'. The bottoms of the vapor separation chambers 12, 12' are connected by conduits 14, 14' which include liquid traps 15, 15' to receiving vessels 16, 16' which form a part of the evaporators E, E'. In actual practice the traps 15, 15' should be embedded in insulation for a purpose to be described hereinafter. The insulation has not been shown in the drawings, so that the parts of the apparatus will be more readily visible.

Each generator-absorber A, A' has an absorbent receiving chamber formed by the outer cylindrical walls of vessels A, A', the outer cylindrical walls of the heat exchange vessels 18, 18' and end closures (not shown) welded to the cylindrical walls. The annular chambers so formed are provided with suitable trays (not shown) having openings through the walls thereof and being welded to the inner and outer cylindrical walls of the annular chambers. These trays support any well known solid absorbent such as strontium chloride which will absorb the refrigerant vapor such as ammonia, which solid absorbent may be charged into the absorption chambers in any manner well known to the art.

The heat exchange vessels 18, 18' are formed of inner and outer concentric cylindrical walls 55 having end closures welded thereto and form

an annular receiving chamber for an indirect cooling fluid of the indirect cooling circuit for the generator-absorbers A, A', the construction and operation of which will be described in more detail hereinafter. In the cylindrical space formed by the inner cylindrical walls of the heat exchange vessels 18, 18' are electric heating cartridges 20, 20' of any suitable construction known to the art.

The upper end of each of the annular heat exchange chambers of the generator-absorbers A, A' is connected by conduits 34, 34' to the secondary condensers 36, 36'. The secondary condensers 36, 36' have a continuous downward slope throughout and lead to a reservoir 38. The reservoir 38 is connected by a conduit 40 to a valve chamber 42. The valve chamber 42 is connected by conduits 44, 44' to the lower end of the annular heat exchange vessels 18, 18' for the generator-absorbers A, A'. The valves 46, 46' are designed to be operated by a snap acting device 48 of any suitable construction.

The evaporators E, E', as shown in Figure 1, include conduits 50, 50' extending vertically downward from the bottom of the receiving vessels 16, 16'. As shown in Figure 3 these conduits are embedded in insulation for a purpose to be described hereinafter. From the lower end of each of the conduits 50, 50', extend a pair of serpentine conduits 51, 51' and 52, 52' which slope upwardly in general vertical planes and enter the receiving vessels 16, 16' at points above the points of connection of the conduits 50, 50'. The conduits 51, 51' are in thermal contact with an ice freezing chamber 54, while the conduits 52, 52' have heat exchange fins thereon for box cooling purposes. The operation of the evaporators E, E' will be described in more detail hereinafter.

Thermostatic bulbs 56, 56' contact the outer surfaces of generator-absorbers A, A' and are connected by capillary tubes 58, 58' to bellows 60, 60', which upon expansion and contraction are adapted to operate the snap acting device 48. The bulbs 56, 56', tubes 58, 58' and bellows 60, 60' are filled with a suitable vaporizable fluid so that the bellows 60, 60' will expand and contract upon variations in temperature of the bulbs 56, 56' as is well known in the art. A snap acting switch 62 of any well known construction is positioned to be actuated by the snap acting device 48.

A thermostatic bulb 64 is positioned in contact with the ice freezing vessel 54 and is responsive to the temperature of that vessel. The bulb 64 is connected by a capillary tube 66 to a bellows 68. The bulb 64, tube 66 and bellows 68 are filled with suitable vaporizable fluid so that the bellows 68 will expand and contract upon variations in temperature of the ice freezing chamber 54 as is well known in the art. The bellows 68, upon expansion and contraction, is adapted to actuate a snap acting device 70 which in turn operates the valve 72 in the conduit 48 and an electric switch 74.

One side of the power line is connected to one side of the switch 74. The other side of the switch 74 is connected by suitable conductors as shown to two of the contacts of the switch 62. The other two contacts of the switch 62 are connected by suitable conductors to one side of the electric heating cartridges 20, 20', the other side of which is connected to the other side of the power line.

The indirect cooling circuit for the generator-

absorbers A, A' which are formed by the heat exchange vessels 18, 18', conduits 34, 34', secondary condensers 36, 36', storage vessel 38, conduit 40, valve chamber 42 and conduits 44, 44', is suitably charged with a vaporizable liquid such as methyl chloride. The pressure within the indirect cooling circuit is not high so that the snap acting device 48 may be led into the interior of the valve chamber 42 through a suitable flexible joint 76.

The refrigerating apparatus just described and shown diagrammatically in Figure 1 is adapted to be arranged so as to be mounted in a domestic refrigerator cabinet as shown in Figure 3. The cabinet comprises a back insulated wall 80, lower insulated wall 82, front access door 84 and top insulated wall 86. At the rear of the cabinet is provided a flue 88 for the circulation of air over the heat rejecting parts of the apparatus. An opening 90 at the bottom of the flue 88 provides for the entrance of cooling air and a screen 92 at its top provides for its exit. The generator-absorbers A, A' are imbedded in insulation 93, and are arranged at the sides of the flue 88 so as not to interfere with the air circulation. The primary condensers C, C' extend across the flue 88 near its upper end and substantially at the same height as the evaporators E, E' and the secondary condensers 36, 36' are similarly arranged below the primary condensers.

The collecting vessels 16, 16' are imbedded in an insulating enclosure 94 for an opening in the back of the cabinet through which opening the evaporator is adapted to pass when the apparatus is assembled with the cabinet. An insulating gasket 96 is provided for sealing the space between the closure 94 and the opening in the back of the cabinet.

As shown in Figure 1 the valve 72 is open and the switch 74 is closed. The switch 62 is set so that electricity will be conducted to the heating cartridge 20 of the generator-absorber A which will be heated. The bulb 60 is contracted and the bulb 60' is expanded by a previous heating of the generator-absorber A' as will be described hereinafter. Thus the snap acting device will be positioned to the left, the valve 48 will be closed and the valve 46' open.

With the control set as in Figure 1 the heating of the generator-absorber A will drive refrigerant vapor from the solid absorbent contained therein. The refrigerant vapor thus evolved will pass by the conduit 10 and conduit 11 to the condenser C where it will condense and the heat of condensation will be carried away by air flowing over the heat rejecting fins mounted upon the tubes of the condenser.

When sufficient refrigerant vapor has condensed in the condenser to fill the trap 13 up to the junction of the conduits 10 and 11, slugs of this condensed refrigerant will be trapped between slugs of refrigerant vapor flowing upwardly through the conduit 11 and will be raised into the vapor separation chamber 12. In the vapor separation chamber 12 the vapor will separate from the liquid refrigerant and pass to the upper end of the condenser C where it is condensed and flows into the trap 13 to be raised into the vapor separation chamber 12 as previously described in connection with the first refrigerant vapor entering the condenser C.

The liquid refrigerant will collect in the bottom of the vapor separation chamber 12 and flow through conduit 14 to the collecting vessel 16 by gravity flow. The liquid trap 15 is provided

to prevent any vapor from the vapor separation chamber from entering the collecting vessel 16. The liquid refrigerant entering the collecting vessel 16 will fill the conduits 50, 51 and 52 as well as the collecting vessel itself.

During the heating of the generator-absorber A the auxiliary cooling liquid in the annular heat exchange chamber 18 of the generator-absorber A will quickly vaporize and flow by conduit 34 into the secondary condenser 36. The air flowing over the fins of the condenser 36 will carry away the heat of condensation of the auxiliary fluid whereby it will condense and flow downwardly through the tubes of the condenser 36 into the reservoir 38. This liquid auxiliary cooling fluid cannot return to the generator-absorber A at this time because the valve 46 is closed.

In the meantime absorption of refrigerant vapor is taking place in the generator-absorber A' in a manner which will be described in connection with the absorption which takes place in the generator-absorber A when the control operates to shift the generator-absorber A from the generating phase to the absorption phase and the generator-absorber A' from the absorption phase to the generating phase.

When sufficient refrigerant is driven from the absorbent in the generator-absorber A the heat from the heating cartridge 20 will no longer be utilized in evolving refrigerant vapor from the absorbent in the generator-absorber A and it will rise in temperature. This rise in temperature will be quite abrupt even though the heat supplied to the generator-absorber A remains constant. This comes about by reason of the fact that while refrigerant is being driven from the solid absorbent the heat supplied thereto is being utilized to vaporize the refrigerant and when the refrigerant is vaporized the heat supplied quickly raises the temperature of the generator-absorber to a much higher value.

This will cause the liquid in the bulb 56 to vaporize whereby the bellows 60 will be expanded. At this time the bellows 60' will be in contracted position because absorption is taking place in the generator-absorber A' and the fluid in the bulb 56' will be condensed. Expansion of the bellows 60 will push the snap acting device 48 to the right which will operate the switch 62 to de-energize the heating element 20 and to energize the heating element 20'. At the very same time it will operate to open the valve 46 and to close the valve 46'.

The indirect cooling system is charged with sufficient auxiliary cooling medium that the reservoir 38 will always contain auxiliary cooling medium in liquid form. When the control operates to open the valve 46 the liquid in the reservoir 38 will be dumped into the annular heat exchange chamber 18 of the generator-absorber A. Since the generator-absorber A is hot at this time the auxiliary cooling liquid will be quickly vaporized by the transfer of heat of vaporization of the auxiliary liquid from the generator-absorber A and it will thus be quickly cooled. The cooling of the generator-absorber A will reduce the vapor pressure therein and the solid absorbent therein will begin to absorb refrigerant vapor and vaporization of the liquid refrigerant in the evaporator E will begin.

The refrigerant vapor evaporating in the evaporator E will return to the generator-absorber A by conduit 14, liquid trap 15, vapor separation chamber 12, conduit 11 and conduit 10. It may

here be pointed out that the liquid refrigerant contained in the liquid trap 15 must first evaporate. The traps 13, 15' are preferably insulated so that the evaporation of the liquid refrigerant therein will not condense moisture on the tubes forming the traps.

As absorption proceeds in the generator-absorber A, the heat of absorption is transferred to the auxiliary cooling liquid in the annular heat exchange chamber 18. This vaporizes the auxiliary liquid and this vapor flows to the condenser 36 by conduit 34. Here the vapor is condensed and the heat of condensation carried away by air flowing over the heat rejecting fins of the condenser 36. The tubes of the condenser 36 have a continuous downward slope and the liquid auxiliary cooling fluid returns to the reservoir 38 to be returned in due course to the annular heat exchanger chamber 18 for further cooling action.

The refrigerant which is evaporating in the evaporator E at this time will cool the conduits 50, 51 and 52 which will in turn cool the ice freezing chamber 54 and freeze the contents thereof as well as cool the air in the refrigerator compartment or food storage space. Since the conduit 50 is insulated no evaporation will take place therein. The conduit 51 being in contact with the freezing chamber 54 and the conduit 52 being in heat exchange with the air in the food storage compartment, a comparatively rapid evaporation of liquid refrigerant will take place therein. This will cause the liquid in conduits 51 and 52 to be raised upwardly so that a positive circulation of the liquid refrigerant will take place. This will augment the cooling effect of the evaporator.

As the evaporation and absorption is taking place in the evaporator E and the generator-absorber A, the generator-absorber A' is being heated by the heating element 20'. Vapor is being driven from the solid absorbent in the generator-absorber A', condensed in the condenser C' and collected in the evaporator E' as previously described in connection with the evaporation of vapor from the generator-absorber A.

By the time that substantially all the liquid refrigerant in the evaporator E has evaporated the refrigerant vapor will be driven from the solid absorbent in the generator-absorber A'. This will cause the medium in the bulb 56' to expand the bellows 60' in the manner previously described in connection with the generator-absorber A. The snap acting device 48 will be moved to the left as viewed in Figure 1 whereby the valve 46 will be closed, the valve 46' opened and the switch 62 operated to energize the heating cartridge 20 and de-energize the heating cartridge 20'. This will cause vaporization to take place in the generator-absorber A and absorption in the generator-absorber A' which will proceed as previously described.

The frozen ice in the ice freezing chamber 54 will act as a cold hold over device and will cooperate with the evaporation taking place in one evaporator while hot refrigerant is being supplied to the other to hold the temperature of the food storage space substantially constant.

The control will function to operate alternately, the generator-absorbers A, A' on the generating period and on absorption period as just described until the temperature of the ice freezing chamber 54 goes below a predetermined limit which is very substantially below the temperature of the air in the food storage compartment. At that time the bulb 64 will operate to collapse the bellows 68

and operate to close the valve 72 and open the switch 74. This will operate to de-energize that generator-absorber which is then being energized and to stop the flow of cooling fluid in the indirect cooling circuit.

The liquid cooling medium in the annular heat exchange chamber of the generator-absorber which has been operating on the absorption cycle will soon vaporize due to the heat of absorption and will pass through the secondary condenser where it will be condensed. Since the tubes of the secondary condenser slope toward the reservoir 38, this condensed liquid cannot return to the cooling space of the generator-absorber being cooled, but will flow to the reservoir 38 and be trapped out of the circuit by the closed valve 72. When the absorption of refrigerant vapor in the generator-absorber being cooled ceases, no more liquid refrigerant will evaporate in the evaporator of that unit. Thereafter the temperature of the air in the food storage compartment and consequently the temperature of the freezing chamber 54 will slowly rise until the control bulb 68 again acts to open the valve 72 and close the switch 74. The two units will then operate cyclicly as previously described.

This invention can be applied to a single intermittently operating absorption unit of the general type disclosed in connection with Figures 1 and 3. Figure 2 shows such a modification.

The same reference characters will be applied to Figure 2 as applied to Figures 1 and 3 insofar as they apply. The generator-absorber A is charged with strontium chloride as the absorbent and ammonia as the refrigerant and the indirect cooling system is charged with methyl chloride as in the modification of Figure 1. The bellows 60 is connected to the snap acting device 48 by a lost motion connection and the switch 62 is modified in that it has only two contacts. One contact of the switch is connected to one side of the power line, the other to one side of the heating element 20. The other side of the heating element 20 is connected to the other side of the power line. One of the valves of the valve chamber 42 as shown in Figure 1 is omitted, leaving only the valve which controls the opening to the conduit 44.

The snap acting device 48 and the bellows 60 are so adjusted that the snap acting device 48 will be snapped to a position opposite that shown in Figure 2 by the high temperature resulting at the end of the generating phase of the generator-absorber A as described in connection with Figure 1 but will not be snapped to the position shown in Figure 2 until the bulb 56 has reached the highest room temperature likely to be encountered, for a purpose to be described hereinafter.

In Figure 2 the evaporator shown in Figure 1 has been combined into a single evaporator so that the water freezing chamber 54 will act as a cold hold over in a manner similar to that of Figure 1. In this case the evaporator will have two conduits 50, two conduits 51 and two conduits 52.

As shown in Figure 2 the bellows 60 is contracted and the snap acting device 48 is positioned to the left so that the valve in the chamber 42 is closed as is the snap acting switch 62.

The generator-absorber A will be on the generating phase and vapor being evolved therefrom is condensed and raised to the vapor separation chamber 12 from whence it will flow to the evaporator E as in the modification of Figure 1. When the refrigerant vapor is driven from the

absorbent in the generator-absorber A its temperature will quickly rise as described in connection with Figure 1 and the bellows 60 will expand to move the snap acting device 48 to the right which will open the valve 46 as well as the snap acting switch 62 so that the heating element 20 is de-energized.

The opening of the valve 46 will cause the liquid cooling medium in the reservoir 38 to be dumped into the annular heat exchange chamber 18 of the generator-absorber A so that it will be quickly cooled as described in connection with the modification of Figure 1. This will cause the vapor pressure in the generator-absorber A to be reduced and absorption of refrigerant vapor will take place therein and evaporation of the liquid refrigerant in the evaporator E in the same way as described in connection with the modification of Figure 1, until all of the liquid refrigerant in the evaporator E has been absorbed in the generator-absorber A.

When this occurs absorption will cease in the generator-absorber A with the result that no more heat will be generated therein and its temperature will be lowered to substantially room temperature by the circulating cooling medium. This will cause the fluid in the bulb 56 to contract sufficiently to collapse the bellows 60 and to shift the snap acting device 48 back to the left as shown in Figure 2. The generator-absorber A will thus automatically operate alternately on the absorption and generating phases as the temperature thereof rises and falls without the necessity of providing any additional control. However, it is preferable that a control like that shown in Figure 1 be provided. Thus when the temperature of the ice freezing chamber 54 is lowered to a predetermined degree by the production of refrigeration in the evaporator E, the bellows 68 will contract to operate the snap acting device 10 to open the switch 74 and close the valve 72 as described in connection with Figure 1. The apparatus will then cease operation until the temperature of the food storage chamber rises sufficiently to raise the temperature of the ice freezing chamber to expand the fluid in the bulb 56 sufficiently to operate the snap acting device in the reverse direction, hence closing the switch 74 and opening the valve 72 as described in connection with Figure 1.

From the foregoing it can be seen that this invention provides an arrangement for raising the condensate from the bottom of the condenser to a higher level whereby it can be led to the top of the evaporator by gravity flow, thus rendering it possible to have the condenser at the same level or below the evaporator which leads to the production of a more compact arrangement of the parts of the apparatus insofar as vertical height is concerned. This renders it possible to assemble the unit with a domestic refrigerator cabinet so that a greater part of the cabinet space can be utilized for food storage purposes for any particular capacity unit.

While I have shown but a number of embodiments of my invention it is to be understood that these embodiments are to be taken as illustrative only and not in a limiting sense. I do not wish to be limited to the particular structure shown and described but to include all equivalent variations thereof except as limited by the scope of the claims.

I claim:

1. A refrigerating apparatus comprising a generator-absorber charged with a refrigerant and

an absorbent therefor, means for heating said generator-absorber to evolve refrigerant vapor from the absorbent, means for liquefying at least a portion of said refrigerant vapor and means for passing refrigerant vapor directly from said generator-absorber into said liquid refrigerant for raising the liquid refrigerant from said liquefying means to a higher level.

2. An absorption refrigerating apparatus comprising a generator charged with a refrigerant and an absorbent therefor, means for heating said generator to evolve refrigerant vapor from the absorbent, a condenser, and a conduit for leading said refrigerant vapor from said generator to said condenser, a portion of said conduit being constructed and arranged to receive condensed refrigerant from said condenser and vapor from said generator, the apparatus being so arranged that said refrigerant vapor will raise the condensed refrigerant to a higher level.

3. An absorption refrigerating apparatus comprising a generator charged with a refrigerant and an absorbent therefor, means for heating said generator to evolve refrigerant vapor from said absorbent, a condenser, an evaporator, a conduit including a vapor separation chamber above the bottom of said condenser for leading said refrigerant vapor from said generator to said condenser, said conduit being constructed and arranged to receive liquid refrigerant from said condenser and refrigerant vapor from said generator, the apparatus being so arranged that the refrigerant vapor flowing toward said condenser will raise said liquid refrigerant to said vapor separation chamber and means for leading said liquid refrigerant from said vapor separation chamber to said evaporator by gravity.

4. In combination, a domestic refrigerator cabinet, an absorption refrigerating apparatus associated therewith including a generator, a condenser above said generator and an evaporator above the bottom of said condenser, means for leading refrigerant vapor from said generator to said condenser, said means including a conduit so constructed and arranged as to receive liquid from said condenser and vapor from said generator, the apparatus being so arranged that the vapor flowing to said condenser will raise the liquid from the condenser to a level from which it will flow by gravity to said evaporator.

5. An absorption refrigerating apparatus comprising a generator charged with a refrigerant and an absorbent therefor, means for heating said generator for evolving refrigerant vapor from said absorbent, a condenser, an evaporator, conduit means including a vapor separation chamber above the bottom of said condenser for leading said vapor to said condenser, said conduit means also including a vapor lift pump constructed to receive liquid refrigerant from said condenser and to utilize vapor flowing to said condenser for raising said liquid refrigerant to said vapor separation chamber and means for leading said liquid refrigerant from said vapor separation chamber to said evaporator by gravity.

6. That method of operating an absorption refrigerating apparatus which comprises, evolving refrigerant vapor from absorbent in a place of evolution at one level, flowing said vapor to a place of condensation at another level, liquefying the refrigerant vapor in said place of condensation, passing the vapor flowing to said place of condensation into the liquefied refrigerant, utilizing the vapor for moving the liquefied refrigerant to a place of evaporation, evaporating the

liquefied refrigerant in said place of evaporation and absorbing the evaporated refrigerant in said place of evolution.

7. That method of operating an absorption refrigerating apparatus which comprises, evolving refrigerant vapor from absorbent in a place of evolution at one level, flowing said vapor to a place of condensation at another level, liquefying the refrigerant vapor in said place of condensation, passing the vapor flowing to said place of condensation into the liquefied refrigerant, utilizing the vapor for moving the liquefied refrigerant to a place of evaporation, evaporating the liquid refrigerant in said place of evaporation, absorbing the evaporated refrigerant into the absorbent in the place of evolution and controlling the reversal from evolution to absorption by the temperature of the place of evolution.

8. That method of operating an absorption refrigerating apparatus of the type having two places of evolution and absorption, two places of condensation and two places of evaporation which comprises, evolving refrigerant vapor from an absorbent in one place of evolution and absorption, passing the refrigerant vapor to the first place of condensation, liquefying the vapor in the first place of condensation, passing the vapor flowing to the first place of condensation into liquid refrigerant from the first place of condensation, utilizing the vapor to move the liquid refrigerant to the first place of evaporation, evaporating the liquid refrigerant in said first place of evaporation, absorbing the evaporated refrigerant into the absorbent in the first place of evolution and absorption, said evaporation step being carried out while evolution and liquefaction is taking place in the second places of evolution and absorption, and condensation, and controlling the reversal of evolution and absorption by the temperature of the place of evolution and absorption in which evolution is taking place.

9. In combination, a domestic refrigerator cabinet having a food storage compartment and an apparatus compartment including an air flue, a refrigerating apparatus assembled with said cabinet including an evaporator in said food storage compartment, a generator-absorber and a condenser in said apparatus compartment, the top of said evaporator being positioned at a higher level than the bottom of said condenser, a conduit for leading refrigerant vapor from said generator-absorber to said condenser, said conduit including a vapor lift pump constructed to receive liquid refrigerant from the bottom of said condenser and vapor from said generator-absorber, the arrangement being such that the vapor from the generator-absorber raises liquefied refrigerant from the bottom of the condenser to the top of said evaporator.

10. In combination, a domestic refrigerator cabinet having a food storage compartment and an apparatus compartment including an air flue, a refrigerating apparatus associated with said cabinet including an evaporator in said food storage compartment, a generator-absorber and a condenser in said apparatus compartment, the top of said evaporator being positioned at a higher level than the bottom of said condenser, a conduit for leading refrigerant vapor from said generator-absorber to said condenser, said conduit including a vapor lift pump and a vapor separating chamber with its vapor space connected to the top of said condenser, said vapor lift pump being so constructed and arranged as to receive liquid from the bottom of said con-

denser and so that vapor from said generator-absorber raises the liquid refrigerant to said vapor separation chamber and means for flowing the liquid refrigerant from the vapor separation chamber to the top of said evaporator by gravity, said last mentioned means including a liquid trap.

11. That method of operating an absorption refrigerating apparatus which comprises, evolving refrigerant vapor from an absorbent by the application of heat, flowing vapor thus evolved to a place of condensation, liquefying vapor in the place of condensation, passing evolved refrigerant vapor into the liquefied refrigerant from the place of condensation to raise the liquefied refrigerant to a place for the separation of liquid and vapor, separating the liquid refrigerant from the refrigerant vapor in the place of separation and passing the refrigerant vapor to the place of condensation while passing the liquid refrigerant to a place of evaporation and preventing the flow of refrigerant vapor to the place of evaporation.

12. An absorption refrigerating apparatus comprising a generator charged with a refrigerant and an absorbent therefor, means for heating said generator to evolve refrigerant vapor from the absorbent, a condenser, an evaporator, conduit means including a vapor separation chamber above the bottom of said condenser for leading vapor evolved from the absorbent in the generator to said condenser, said conduit means also including a vapor lift pump constructed to receive liquid refrigerant from said condenser and to utilize vapor flowing to said condenser for raising the liquid refrigerant condensed in the condenser to the vapor separation chamber wherein the vapor is separated from the liquid refrigerant and flows to said condenser and means for leading the liquid refrigerant from the vapor separation chamber to said evaporator including means for preventing vapor from flowing to the evaporator.

13. A refrigerating apparatus comprising a generator-absorber charged with a refrigerant and an absorbent therefor, means for heating said generator-absorber to evolve refrigerant vapor from the absorbent, means for liquefying at least a portion of said refrigerant vapor, means for passing refrigerant vapor directly from said generator-absorber into said liquid refrigerant for raising the liquid refrigerant from said liquefying means to a higher level and means for leading the vapor passed into the liquid refrigerant to said liquefying means.

14. An absorption refrigerating apparatus comprising a generator charged with a refrigerant and an absorbent therefor, means for heating said generator to evolve refrigerant vapor from the absorbent, means for liquefying at least a portion of said refrigerant vapor, means for passing refrigerant vapor directly from said generator into said liquefied refrigerant for raising the liquefied refrigerant from said liquefying means to a higher level and means for leading the vapor passed into the liquid refrigerant to said liquefying means.

15. An absorption refrigerating apparatus comprising a generator charged with a refrigerant and an absorbent therefor, means for heating said generator to evolve refrigerant vapor from the absorbent, a condenser, a conduit for leading said refrigerant vapor from said generator to said condenser, a portion of said con-

duit being constructed and arranged to receive condensed refrigerant from said condenser and vapor from said generator, the apparatus being so arranged that said refrigerant vapor will raise the condensed refrigerant to a higher level and the vapor used to raise the liquid refrigerant to said condenser is conducted to said condenser.

16. An absorption refrigerating apparatus comprising a generator charged with a refrigerant and an absorbent therefor, means for heating said generator to evolve refrigerant vapor from said absorbent, a condenser, an evaporator, a conduit including a vapor separation chamber above the bottom of said condenser for leading said refrigerant vapor from said generator to said condenser, said conduit being constructed and arranged to receive liquid refrigerant from said condenser and refrigerant vapor from said generator, the apparatus being so arranged that the refrigerant vapor flowing to said condenser will raise said liquid refrigerant to said vapor separation chamber, and means for leading said liquid refrigerant from said vapor separation chamber to said evaporator by gravity.

17. An absorption refrigerating apparatus comprising a generator charged with a refrigerant and an absorbent therefor, means for heating said generator to evolve refrigerant vapor from the absorbent, means for liquefying said refrigerant vapor, means including a vapor lift pump for utilizing refrigerant vapor flowing from said generator to said liquefying means for raising the liquefied refrigerant to a higher level and means for leading vapor from said vapor lift pump to said liquefying means.

18. That method of operating an absorption refrigerating apparatus which comprises, evolving refrigerant vapor from absorbent at one level, flowing said vapor to a place of condensation at another level, liquefying the refrigerant vapor in said place of condensation, utilizing the buoyancy of the vapor flowing to said place of condensation for raising the liquefied refrigerant to a place of evaporation at a third level, evaporating the liquid refrigerant in said place of evaporation, absorbing the evaporated refrigerant into the absorbent in the place of evolution and controlling the reversal from evolution to absorption by the temperature of the place of evolution.

19. That method of operating an absorption refrigerating apparatus of the type having two places of evolution and absorption, two places of condensation and two places of evaporation which comprises, evolving refrigerant vapor from an absorbent in one place of evolution and absorption, passing the refrigerant vapor to the first place of condensation, liquefying the vapor in the first place of condensation, utilizing the buoyancy of the vapor flowing to the first place of condensation for raising liquid refrigerant from the first place of condensation into the first place of evaporation, evaporating the liquid refrigerant in said first place of evaporation, absorbing the vapor into the absorbent in the first place of evolution and absorption, said evaporation step being carried out while evolution and liquefaction is taking place in the second places of evolution and absorption, and condensation, and controlling the reversal of evolution and absorption by the temperature of the place of evolution and absorption in which evolution is taking place.

20. That method of operating an absorption refrigerating apparatus which comprises, evolv-

ing refrigerant vapor from an absorbent by the application of heat, flowing vapor thus evolved to a place of condensation, liquefying the vapor in the place of condensation, utilizing the buoyancy of the evolved refrigerant vapor for raising the liquefied refrigerant to a place for the separation of liquid and vapor, separating the liquid

refrigerant from the refrigerant vapor in the place of separation, passing the liquefied refrigerant to a place of evaporation and preventing the flow of refrigerant vapor to the place of evaporation.
